J. H. MEINTS

DEVICE FOR REMOVING CARBON

Filed Dec. 31, 1924

Patented May 4, 1926.

1,583,001

UNITED STATES PATENT OFFICE.

JOHN H. MEINTS, OF BEATRICE, NEBRASKA.

DEVICE FOR REMOVING CARBON.

Application filed December 31, 1924. Serial No. 759,132.

To all whom it may concern:

Be it known that I, JOHN H. MEINTS, a citizen of the United States, residing at Beatrice, in the county of Gage and State 5 of Nebraska, have invented certain new and useful Improvements in Devices for Removing Carbon, of which the following is a specification.

This invention relates to devices for removing carbon from internal combustion engines and has as its general object to provide a device which may be conveniently used for this purpose and which will obviate the necessity of resorting to the tedious 15 scraping of the carbon by hand which is the method usually followed.

Another object of the invention is to provide a device of the class referred to embodying an abrading element actuated 20 through the medium of a flexible shaft driven from a stationary motor, which will enable the user of the device to conveniently apply the abrading element to the surfaces from which carbon is to be removed, without the necessity of moving the 25 motor from place to place or being otherwise inconvenienced.

Another object of the invention is to so construct the device that the abrading element may be conveniently removed, when it becomes worn, and a new one substituted 30 therefor.

In the accompanying drawings:

Figure 1 is a perspective view of the device embodying the invention.

Figure 2 is a detail longitudinal sectional view taken substantially on the line 2—2 of Figure 1, looking in the direction indicated by the arrows.

Figure 3 is a similar view on the line 3—3 of Figure 1.

In the drawings, the numeral 1 indicates an electric motor and the numeral 2 the shaft of the motor, and the end of the shaft 45 is rotatably fitted in a sleeve 3 which is exteriorly threaded at one end, as indicated by the numeral 4, the shaft being provided with a shoulder 5 against which one end of the sleeve may abut to prevent longitudinal 50 movement of the sleeve upon the shaft in one direction, and being provided likewise with a circumscribing collar 6 against which the other end of the sleeve may abut to prevent longitudinal displacement in the other 55 direction. The extremity of the shaft is formed with a diametric groove indicated by

the numeral 7 and this groove accommodates a diametric tongue 8 formed at the end of a coupling member 9 which is rotatably mounted in a sleeve 10 fixed at one end of a sheath 11 housing the flexible shaft 12, the end of the shaft being connected to the said coupling member 9 and the sleeve being 60 interiorly enlarged at one end to accommodate a shoulder 13 formed upon the said coupling member whereby to prevent inward movement of the member into the sleeve. The sleeve is swaged at its enlarged end as indicated by the numeral 14 whereby to rotatively retain thereon a union 15 which is interiorly threaded as at 16 to fit the threads 4 of the sleeve 3, the parts being 65 in this manner so connected that while the sleeve 10, the sleeve 3, and the union 15 remain stationary, the shaft 2, coupling member 9, and shaft 12 will freely rotate and rotary motion is thus communicated to the flexible shaft from the motor shaft.

Fixed to the other end of the sheath 11 is a sleeve 17 which is interiorly enlarged at 70 its outer end to provide a shoulder 18 against which seats a collar 19 formed upon a coupling member 20 corresponding to the member 9 previously described, the coupling member 20 having connected to it the other end of the flexible shaft 12. The outer end of the coupling member 20 is provided with a diametric tongue 21 which fits in a diametric groove 22 formed in one end of a shaft 23 rotatably mounted in a sleeve 24 75 connected to the end of the sleeve 17 by a coupling 25 threaded onto the end of the said sleeve 24 and swiveled to the outer end of the sleeve 17, as shown in Figure 2 of the drawings. The outer end of the shaft 23 is 80 threaded as indicated by the numeral 26 and a nut 27 is threaded onto this end of the shaft and is adjusted to nearly abut the outer end of the sleeve 24.

The numeral 28 indicates in general the 85 abrading element of the device and the same comprises an annular head 29, the opening of which is of greater diameter than the shaft 26, tufts of wire bristles 30 being secured at their inner ends in the channel of the head, as shown in Figure 2. Washers 31 and 32 are disposed against the opposite sides of the head 29, the washer 31 engaging against the nut 27, and a nut 33 being threaded onto the end of the shaft 23 and tightened 90 to bear against the other washer 32, whereby to clamp the head 29 between the washers 95

31 and 32 and thus secure the head in place and for rotation with the shaft 23.

In the use of the device, the flexible shaft is grasped by the sleeves 17 and 24 and the 5 rotary abrading element 28 is applied peripherally to the surfaces from which carbon is to be removed, and it will be evident that due to the employment of a flexible shaft to transmit motion to the abrading ele- 10 ment, the carbon may be removed from all the parts of the engine which are encrusted therewith, rapidly and effectually, the flexibility of the motion transmitting means permitting of free use of the abrading element.

15 Having thus described the invention, what I claim is:

In a device of the character described, a sleeve formed with a bore having an enlarged rear end portion forming an annular

20 seat, a rotatable shaft extending through the bore of said sleeve and having its rear end portion provided with an abutment seated in said seat to prevent forward sliding of the shaft, the rear end of said shaft being 25 adapted for engagement with drive means and the forward end portion of the shaft being threaded and extending from said sleeve, a nut screwed upon the extended forward end portion of said shaft to engage the 30 forward end of the sleeve and prevent rearward sliding of said shaft, a cleaning element fitted upon said shaft against said nut, and a nut screwed upon the outer end portion of said shaft and engaging said 35 cleaning element to clamp the same against the first nut for turning with the shaft.

In testimony whereof I affix my signature

JOHN H. MEINTS. [L.S.]
